Attorney.

UNITED STATES PATENT OFFICE.

ROBERT WILSON, OF HOBART, TASMANIA, AUSTRALIA.

BUILDING OF CONCRETE STRUCTURES.

1,405,650.

Specification of Letters Patent. Patented Feb. 7, 1922.

Application filed June 9, 1920. Serial No. 387,643.

To all whom it may concern:

Be it known that I, ROBERT WILSON, a subject of the King of Great Britain, residing at National Mutual Buildings, Macquarie 5 Street, Hobart, in the State of Tasmania, Commonwealth of Australia, have invented certain new and useful Improvements in and Relating to the Building of Concrete Structures, of which the following is a specification.

This invention has for its object the provision of means for building concrete structures such as foundations of houses, fences or walls either solid or hollow. It further aims 15 at improving and simplifying the work of construction, and provides for the proper support of the operative parts.

According to my invention, a mould is made of metal sheets arranged on angle irons 20 placed upright and slidably held on vertically arranged supports. Means for steady- 25 ing the supports, which may consist of poles, are provided of a simple character, and there is an effective cavity box, of simple construc- 30 tion, which can be inserted medially within the camera on the reinforcement rods.

But in order to fully understand the invention reference is made to the accompanying drawings, in which,

30 Figure 1 is a perspective view of a mould arranged to receive material for the formation of a hollow wall.

Figure 2 shows a mould plate in side elevation fitted on its respective ends with tongue 35 and groove for the purpose of joining up one length of mould to another.

Figure 3 shows the said tongue and groove arrangement in plan view with locking pin in position.

40 Figure 4 is a plan view of a holdfast or distance piece for steadyng the vertical poles.

Figure 5 illustrates a yoke and attached recessed plate at top.

45 Figure 6 is a perspective view of cavity boxes, and

Figure 7 a filling chute and cap to said boxes.

50 Figure 8 shows in plan view the angle of a wall and the disposition of the parts in constructing same.

The sheets 9 are composed of stout metal plating and are fitted with angle irons 10 upon which are lugs 11. Upright poles 12 55 are placed in the ground in lines parallel

with the foundations and the lugs, which are bored with holes to accommodate the poles, are passed over the latter which thus hold the plates 9 vertical.

So that the poles 12 shall be steadied, hold-fasts or distance pieces 13 are used. These are provided near each end with an elliptical opening to facilitate the plates being dropped down the poles. These openings may, if desired, extend to the edge of the plates. To 60 hold same in position such plate end has a clip 14 pivotally attached and with a semi-circular recess therein, of about the same radius as the plate, that closes on the pole and pushes same into the inner end of the elliptical opening 15 where it is held by the clip, each being locked to the piece 13 by a pin in the holes 25. Thus are the mould plates 9 held, but in order to further support the same and to avoid the plates bellying under pressure of the wet filling, I provide yokes 16 at 65 intervals along the mould. To the upper part of each yoke may be fastened a plate 17, that is fashioned as shown in Figure 5, with a medial recess and sideways lugs 18 which bear outwardly against the top of the mould plates while the legs of the yoke embrace the same exteriorly. The yokes bear upon the horizontal irons attached to the sheets. One leg of each yoke is made slightly longer than 70 the other to facilitate placing the same in position, it being understood that both legs overlap the lowest horizontal iron 10, but one 75 will overlap further than the other.

When the inner and outer poles 12 are not 80 exactly opposite the holdfasts 13 will be dispensed with and any suitable means may be used to hold the mould plates 9 in place until the yokes 16 are positioned.

If a hollow wall is desired the cavity boxes 85 19 are employed. These are made from plates bent in U-shape and are joined in series by slightly telescoping one into another. The boxes are placed medially within the mould and can be supported at the top 90 in the medial recess between the yoke lugs 18, the lower end of the boxes meanwhile resting upon the reinforcement rods (not shown). To assist in removing the box sections same are preferably made with a slight 100 taper towards the bottom, say of about one-eighth of an inch.

A feed chute 20 is adapted to ride upon the cavity boxes and to pass the material 105 into the mould at each side thereof. Any 110

length of box can be formed by slightly telescoping one member with the next while lying on its open side but as the cavity box must be closed at each end when in operation 5 the curve of each end member must be outermost. Thus, in order to properly support the union of two open ends I insert the wooden packing 24. The boxes are very simply made and the packing is especially 10 useful in that by removing it after the material has set, the springy sections of the box will tend inwardly thus facilitating the removal of the sections forming the boxes.

In order that the mould sides may be extended, the plates 9 are at one end fitted with 15 two parallel extension plates 21. These plates are preferably attached outside the mould in order to leave the mould plates flush and continuous. Same will constitute 20 a groove and at the other end a tongue 22 is attached which extension or tongue takes into the groove. Both members are perforated at intervals say of three inches to receive pins 23 that hold the two plates together in line. These joints should if possible come opposite each other in the mould 25 sides and the pin can then, if required, be made long enough to pass right through the mould to engage the perforations in the 30 opposite joint.

At wall angles, in order to bring the joints opposite, special mould plate lengths are necessary. If Figure 8 these joints are not opposite and the wall at the corner is 35 solid with the lug 11 outside the outer section of the wall and within the inner section. The poles 12 in the lugs are supported across the corner diagonally by the holdfast shown in dotted lines.

40 When one course has been formed or laid the mould plates are raised on the poles, which are preferably hollow, and secured by pins, inserted in holes provided at intervals in the poles, below the lugs, thus 45 holding the mould plates. The extensions 21 forming the groove are made longer than the tongue 22 to give a degree of flexibility between the parts that will be found useful in arranging the parts upon sloping 50 or uneven ground, and whereby one mould

may be set on a plane below its neighbor. The mould plates, when raised over a completed course, should preferably slightly overlap the top of such course when the fresh filling is poured in, thus minimizing 55 leakage and waste.

Vent openings may be formed between the mould plates 9 at the desired position.

In operation, the poles 12, which are sharpened at the lower ends, are driven into 60 the ground or otherwise secured and the mould plates 9 arranged inside the same. The holdfasts 13 are then adjusted about the poles and the yokes 16 placed over the mould. If a hollow wall is to be made the 65 cavity boxes 19 are assembled and placed medially within the mould and steadied at the top in the recessed plate 17 attached to the yoke. The mould is extended to the required length by joining up the specially 70 tongued and grooved plates and the feed chute is placed over the cavity boxes. Then the material is fed through the chute into the mould which is strengthened and supported at the sides by the yokes 16.

Having now described my invention, what I claim as new and desire to secure by Letters Patent is:—

1. In the construction of concrete walls or foundations, in combination, upright 80 poles along the line of wall outside and supporting mould plates, holdfast plates on and between the poles, an elliptical opening in each plate end, a pivotally mounted clip with a semicircular recess on each end of 85 the plate which is swung around and held to a pole to grip and steady the same.

2. In the construction of hollow concrete walls, cavity boxes in the mould for forming the wall said boxes being formed of a 90 number of addable parts each made of a metal sheet bent into deep U-shape form, the free ends of one member telescoping with the bent end of the next and a rebated liner at the union of the free ends of two members 95 whereby collapsible cavity boxes of varying lengths can be formed.

In testimony whereof I affix my signature.

ROBERT WILSON.
